DESIGN FOR A LADY'S SUIT

Louis W. Goodkind, New York, N. Y.

Application October 10, 1939, Serial No. 87,607

Term of patent 3½ years

To all whom it may concern:

Be it known that I, Louis W. Goodkind, a citizen of the United States and a resident of the city of New York, in the county of Queens and State of New York, have invented a new, original, and ornamental Design for a Lady's Suit, of which the following is a specification, reference being had to the accompanying drawing, forming a part thereof:

Fig. 1 is a front view of a suit showing my new design.

Fig. 2 is a rear view of the suit shown in Fig. 1.

The characteristic feature of my design resides in the combination on the suit disclosed of the specific jacket member having a single tie closure below the lapels which holds the side edges in abutment in association with the specific pocket members arranged on the front, as shown.

I claim:

The ornamental design for a lady's suit, substantially as shown and described.

L. W. GOODKIND.
